METHOD AND APPARATUS FOR CRIMPING
BOX STRAPS

Charles Schmutzer, Irvington, and Kurt Manrodt, Newark, N. J., assignors to Hoffman Beverage Company, Newark, N. J., a corporation of New Jersey

Application June 9, 1939, Serial No. 278,314

11 Claims. (Cl. 140—93)

This invention relates to a method of treating the metallic strap on a wooden shipping case, or the like, so that it remains tight and secure at all times, and to apparatus for performing that method, although the apparatus is not limited to that use.

Shipping cases for bottles and the like are usually made of relatively soft wood, such as poplar or the like, which is subject to substantial expansion and contraction as its moisture content varies, so much so that the flat metal straps, which are used to bind the ends of the case, loosen to a degree which causes arches or loops between the nails, which catch upon the bottle case conveyor, floor, or the like, over which the case moves, or on adjoining cases, and the like, so that the nails are loosened or pulled out. This condition occurs almost immediately after the new cases are put in service, for the wood that is commonly used to make such cases is usually well-seasoned and dried in accordance with good practice, so that the wood is subject to expansion when submitted to moisture, resulting in loosening the straps, no matter how tightly they are bound on the case during the fabricating process.

In accordance with this invention, the metal straps of a bottle case or the like are crimped at spaced intervals, preferably between the nails which secure the straps to the wood, so as to not only take up any existing slack in the straps, but to provide flexible expansion and contraction grooves which permit their expansion and take up the subsequent contraction, with the result that the straps remain substantially uniformly tight, do not project above the adjacent surface of the case so as to catch when moved, and do not loosen the fastening nails so that they will pull out during ordinary handling of the case. Accordingly, the crimps provide ample leeway for normal expansion and contraction of the wood during ordinary usage of the case.

The apparatus for crimping the straps of the case according to the aforementioned method includes two dies, one of which may be substantially stationary and the other reciprocating, so that the end of a case may be placed between the dies and the reciprocating die forces the corresponding side of the case against the stationary die for crimping of the strap while simultaneously crimping the corresponding opposite side of the strap in its compressive movement. The dies are formed with ridges spaced apart substantially the distance between the nails holding the straps to the wood, but displaced half that distance, so that the ridges engage the straps approximately

5 between the nails. The ridges are of substantial height so that they not only crimp the strap but also depress the wood beneath the strap at the crimp. In this way the straps are drawn more tightly by reason of the shortening of their effective lengths, and the crimps draw out of the corresponding depressions as the box expands, due to absorption of moisture and the like, and conversely, the crimps extend further into the 10 corresponding depressions in the wood as the case contracts due to subsequent drying out of the wood. The apparatus is so constructed as to permit rapid treatment of a plurality of cases at the same time whereby the cases may be improved for service when new and may be rendered effective for a longer time when old.

For a more complete understanding of the invention, reference may be had to the accompanying drawings, in which:

Figure 1 is an elevation of a preferred form of the apparatus of this invention, and illustrates the two dies in position for cooperative relation with the ends of a bottle case fitted with straps;

Fig. 2 is a fragmentary section through the apparatus, as seen along the line 2—2 of Fig. 1, and illustrates the preferred arrangement in which two cases may be treated simultaneously;

Fig. 3 is a plan view of the bottle case supporting platforms, guides, and the lower die, as seen along the line 3—3 of Fig. 2;

Fig. 4 illustrates an elevation of a portion of the lower die and the dividing wall or stop between opposite sides of the apparatus for treating two cases simultaneously;

Figs. 5 and 6 are vertical sections therethrough as seen along the line 5—5 and 6—6, respectively, of Fig. 4;

Fig. 7 is a side elevation of a case treated according to the method and in the preferred apparatus of this invention; and

Fig. 8 is a fragmentary end view of a case showing the crimps in the strap thereof.

Referring to Figs. 1, 2 and 3 of the drawings, numeral 10 generally designates a suitable frame preferably formed of steel angles 11 arranged vertically and suitably connected in spaced relation by bolts 12. Extending across the frame 10 is a beam 13 formed of channel irons or the like, and supporting a plate 14 to which is secured by bolts 15 the lower die 15.

As shown particularly in Figs. 4, 5 and 6, this lower die 15 includes a plate 16 to which is riveted two parallel series of spacers 17 clamping between them the die members 18, which are preferably short bars of square section, so positioned

that one of their edges projects above the surface of the adjacent spacers 17 so as to form ridges 19 having a height above the adjacent surfaces of the spacers 17 which is equal to the desired depth of the crimps or grooves to be formed. End plates 17' lock the die members 18 in longitudinal position.

The length of each ridge 19 is approximately equal to the width of the sheet metal strap 20 secured around the ends of a bottle case 21 or the like, as shown in Figs. 7 and 8. The strap 20 is commonly steel, tinned, blued, or otherwise protected against corrosion, and essentially resilient or springy laterally but inextensible longitudinally. In the fabrication of the case 21, the straps 20 are as tightly bound around the ends of the case as is possible and then nailed in place by flat-headed nails 22. The ends of the case are usually recessed the width of the straps 20, and to a depth slightly greater than the thickness of the straps, so that the straps 20 and the heads of the nails 22 do not project above the adjacent surfaces of the case, as is indicated in Fig. 8.

The spacing between the die bars 18, and consequently the ridges 19, is substantially equal to the spacing between the nails 22 securing the strap 20 to the case 21, but the bars 18 are displaced one-half the distance between the nails 22 so that their ridges 19 lie approximately midway between the nails 22, the box 21 being so positioned with respect to the die that the ridges 19 lie in the position described, that is, midway between the nails 22.

Guides 23 and 24, shown particularly in Fig. 3, are mounted on the frame 10 so that the cases 21 are properly positioned with respect to the ridges 19 of the die 15 in the manner described. Guide 24 is preferably in the form of a shoe pivoted at one end 25 on the bracket 26 secured to frame 10, with its inner end 27 urged inwardly by a spring 28 on a stud 29 secured to frame 10, as shown in Fig. 3. The normal position of shoe 24 is such that the spacing between the guide 23 and shoe 24 is less than the depth of the case inserted between them so that the latter is held in proper position with respect to the ridges 19 of the die 15.

As shown particularly in Figs. 1, 5 and 6, the lower die is divided by the lower one of two stop plates 30 secured to the frame 10 so that in effect two dies are formed. The stop plates 30 form abutments against which the ends of two cases lodge and cooperate with the corresponding parts of lower die 15, whereby two cases can be treated simultaneously in the manner to be described.

Positioned below the guide 23 and guide shoe 24 with its inner end adjacent the die, is a horizontal platform 31 upon which a case 21 is adapted to be supported in the apparatus. As shown particularly in Figs. 1 and 2, the opposite ends of the platform 31 are turned downwardly and the inner end thereof is normally positioned flush with or slightly above the upper edges of the die ridges 19, so that a case 21 may be slid over the platform and over the die 15 against the stop plates 30 without catching on the die ridges 19. The inner end of the platform 31 is normally urged in this position by two spaced coil springs 32 each surrounding a rod 33 having a head 34 at its upper end screwed to the platform 31.

The rod 33 is slidable at its lower end through the lower flange 35 of a bracket 36 secured to the frame 10. The head 34 of the rod 33 is enclosed in a sleeve 37 which likewise is slidable through an aperture in the upper flange 38 of bracket 36.

The spring 32 abuts at its lower end the flange 35 and at its upper end the head 34, so as to urge the platform 31 upwardly to the limit permitted by the stop nuts 39 on the rod 33, this limit being such that the inner end of the platform 31 is flush with the ridges 19 or slightly thereabove, as shown in Fig. 2.

The opposite side of the apparatus is provided with a similar platform 31' and identical appurtenant parts for supporting a second case 21 in the manner shown in Fig. 2. Likewise the other side of the machine is fitted with a similar guide 23' and guide shoe 24', corresponding to guide 23 and shoe 24.

15 Journalled in bearings 40 secured on the upper end of the frame 10 is a shaft 41 driven by any suitable power means, such as an electric motor, for example. The center of the shaft 41 between the bearings 40 is provided with an eccentric 42 carrying the two-part eccentric strap 43, one part of which is formed on the upper end of a connecting rod 44. The lower end of connecting rod 44 is provided with a hub 45 journalled on the stub shaft 46, from which is suspended the upper die frame 47. As shown particularly in Fig. 2, this upper die frame is of box structure formed of an I-beam 48 and side plates 49 and is guided for vertical sliding movement between the spaced angle irons 11 constituting opposite sides of the frame 10 of the machine. Accordingly, as shaft 41 rotates the eccentric 42 causes the die frame 47 to reciprocate in a vertical direction.

Suitably secured to the lower surface of the 35 I-beam 48 of the upper die frame 47 is the upper die 50, which is in all respects identical to the lower die 15, except that it is not divided, its length being such as to extend across the width of two straps 20 when there are two corresponding cases 21 simultaneously positioned in the machine against the stop plates 30 as shown in Fig. 2. The ridges 19' of the upper die 50 are aligned with the corresponding ridges 19 of the lower die 15. The throw of the crank 42 is such that the ridges 19 and 19' of respective dies 15 and 50 are brought together the proper distance so as to apply the crimps 51 to the straps 20 on opposite sides of the case 21 of the proper depth, i. e. when the flat surfaces between the die ridges 19 and 19' of the spacers 17 abut flatwise with the corresponding surfaces of the strap 20. Also, the throw of the eccentric 42 is such that the upper die 50 is drawn upwardly a sufficient distance greater than the height of the case 21 to permit free insertion of the case 21 into the apparatus without stopping the machine for that purpose, the upper position of the die being indicated in Figs. 1 and 2.

In operation of the apparatus of this invention 60 according to the aforementioned method, a case 20 is placed on one of the platforms 31 or 31' and pushed inwardly between the vertical guide 23 and shoe 24 against the stop plate 30, the platform 31 being raised by its springs 32 flush with or above the upper edges of ridges 19 of the lower die 15, the platform 31, the stop 30, the guide 23 and the shoe 24 cooperating to position the metal strap 20 over the die 15. It will be understood that the guide 23, in cooperation with the shoe 24, properly positions the case in a sidewise direction over the ridges 19 of the lower die 15 so that they lie approximately midway between the nails 22 securing the strap 20 to the case. This insertion of a case 20 is of course made while the upper die

50 is raised by its eccentric 42 in the manner shown in Figs. 1 and 2.

As the shaft 41 continues to rotate, its eccentric 42 lowers upper die 50 so that its ridges 19' engage the upper strap 20 but do not as yet materially crimp it, for the case is not rigidly supported vertically because of the floating condition of the inner end of the platform 31, due to the resiliency of the springs 32. Accordingly, the upper die 50 continues to force the case downwardly until the springs 32 are compressed and the platform 31 is lowered sufficiently for the ridges 19 of the lower die 15 to engage and crimp the lower portion of the strap 20 of the case 21, whereupon the ridges 19' of the upper die 50 crimp the upper portion of the strap 20 until the upper die 50 has reached the lower limit of its movement as provided by the eccentric 42. The flat portion of the lower die 15, formed by the spacers 17, together with the side plates 17', form the lower stop for the case.

The straps 20 at opposite sides of the case 21 are accordingly simultaneously crimped at spaced intervals in the manner shown in Figs. 7 and 8 to the depth of the ridges 19 and 19'. During this operation, the strap is drawn incidentally more tightly by reason of its decreased effective length and the wood beneath which crimp 51 is depressed in the manner shown particularly in Fig. 8. Thus, as the case expands, the straps 20 may expand in length, the crimps 51 drawing out of the corresponding grooves in the wood, and when the case subsequently contracts, the crimps 51, by reason of the resiliency of the straps 20 creep into the grooves in the wood, so that the straps remain tight under all conditions, and no loosening of the nails 22 results because of pulling by the straps or catching of a loose strap on an object during the handling of the case. Also, the flatwise engagement of the spacers 17 of the dies 15 and 50 with the corresponding surfaces of the straps 20 acts to drive in any loosened or projecting nails 22.

As indicated in Fig. 2, two cases 21 may be treated simultaneously, whereupon they are reversed and the other ends thereof inserted in the apparatus for crimping of the straps in the same way.

While a preferred embodiment of the apparatus for practicing the method is illustrated and described herein, it is to be understood that the invention is not limited thereby, but is susceptible of changes in form and detail within the scope of the appended claims.

It is further to be understood that the term "strap" as employed herein and in the appended claims comprehends within its scope all permanently deformable strips capable of being crimped in situ, whether of flat, round, or other cross section, used for encircling or otherwise wholly or partially binding, shipping or packing cases, boxes, casks, or other containers formed of wood, metal, or other material deformable at the crimp of the binding strips in the manner herein described.

We claim:

1. The method of treating in situ the binding strap previously secured by spaced fastening means to a wooden packing or shipping container, which comprises deforming the strap at least one point between a pair of adjacent fastening means, simultaneously deforming the strap at least one point between another pair of adjacent fastening means, said deformations of the strap being accompanied by simultaneous

deformation of the wood beneath the corresponding strap deformations, whereby the strap is rendered longitudinally elastic in at least one direction.

5 2. In apparatus for crimping the binding strap previously secured to a container, the combination of a support for the container, a deforming member for engaging the strap at one point, a second deforming member for engaging said strap on the opposite side of the container, and means for relatively moving said members toward each other for deforming the strap transversely of its length on opposite sides of the container.

15 3. In apparatus for crimping the binding strap previously secured to a container, the combination of a support for the container, and a deforming member for engaging the strap at one point, a second deforming member for engaging said strap on the opposite side of the container, means for positioning the container on the support to align the strap with the members, and means for relatively moving said members toward each other for deforming the strap transversely of its length on opposite sides of the container.

20 4. In apparatus for crimping the binding strap previously secured to a container, the combination of a support for the container, a deforming member adjacent said support for engaging the strap on the side of the container resting on the support, and means for engaging the opposite side of the container for forcing the said strap on the member to deform the strap.

25 5. In apparatus for crimping the binding strap previously secured to a container, the combination of a support for the container, a deforming member adjacent said support for engaging the strap on one side of the container, a second deforming member for engaging the strap on the opposite side of the container, and means for relatively moving said members toward each other for deforming the strap transversely of its length on opposite sides of the container.

30 6. In apparatus for crimping the binding strap of a container, the combination of a support for the container, having a deforming member associated therewith for engaging the strap on the side of the container resting on the support, a movable second deforming member aligned with said first member for engaging the strap on the opposite side of the container, and means for moving said second member into engagement with the corresponding strap to crimp the same and force the lower strap onto said first member to substantially simultaneously crimp the corresponding strap.

35 7. In apparatus for crimping the binding strap of a container, the combination of a support for the container, a deforming member having a plurality of spaced die ridges for engaging the strap at a plurality of spaced points on one side of the container, a second deforming member having a plurality of spaced die ridges for engaging the strap at a plurality of spaced points on the opposite side of the container, and means for relatively moving said members toward each other for substantially simultaneously deforming the straps on opposite sides of said container at a plurality of spaced points transversely of the length of the strap.

40 8. In apparatus for crimping the binding strap of a container, the combination of a support for the container, a deforming member having at least one ridge for engaging the strap on the side

of the container resting on the support, resilient means normally holding said support in a position not lower than the upper level of the ridge, whereby the container can be supported on the support with the container strap overlying the ridge, and means for moving said container and support against the tension of said resilient means to engage the strap with the ridge for crimping the strap transversely of its length.

9. In apparatus for crimping a container binding strap at points intermediate the means securing the strap to the container, the combination of a fixed die member having a plurality of transverse ridges spaced apart substantially the distance between the strap fastening means, 10 guide means for holding the container with its strap in alignment with said die member and with the ridges thereof positioned intermediate the adjacent fastening means by the strap, a movable second die having a plurality of trans- 15 verse ridges substantially aligned with the ridges of the first die member for engaging the strap on the opposite side of the container, and means for moving said second die member toward said first die member to cause the ridges of the cor- 20 responding die members to substantially simul- 25

taneously crimp the corresponding parts of the strap transversely of its length at points between fastening means therefor.

10. The method of treating the binding strap previously secured to a shipping or packing container, which comprises deforming the strap transversely by means of a deforming element, and deforming the strap transversely at another point longitudinally thereof with a second deforming element while the strap remains engaged by the first deforming element, whereby the strap is rendered longitudinally elastic in at least one direction.

11. In apparatus for crimping the binding strap previously secured to a container, the combination of a support for the container, a deforming member for engaging the strap at one point, a second member for engaging said strap at another point spaced from said first point, and means for relatively moving said members into engagement with said strap for deforming the strap transversely of its length at said spaced points.

CHARLES SCHMUTZER.
KURT MANRODT.
